CLAIM

The ornamental design for a combined wrist rest and integral support pad, as shown and described.

DESCRIPTION

FIG. 1 is a top plan view of a combined wrist rest and integral support pad showing my new design;

FIG. 2 is a bottom plan view, thereof;

FIG. 3 is a right end view, thereof;

FIG. 4 is a left end view, thereof;

FIG. 5 is a front elevational view, thereof;

FIG. 6 is a rear elevation view, thereof; and,

FIG. 7 is a front perspective view thereof, the broken line drawing of a keyboard is for illustrative purposes only and forms no part of the claimed design.
